DESIGN FOR A HOSE SUPPORTER

Leo Zavolner, Brooklyn, N. Y.

Application September 4, 1942, Serial No. 108,132

Term of patent 3½ years

To all whom it may concern:

Be it known that I, Leo Zavolner, a citizen of Russia, residing at Brooklyn, in the county of Kings, city and State of New York, and whose post-office address is 1763 51st Street, Brooklyn, New York city, N. Y., have invented a new, original, and ornamental Design for a Hose Supporter, of which the following is a specification, reference being made to the accompanying drawing, forming a part thereof.

Fig. 1 is a front view of a hose supporter showing my new design;

Fig. 2 is a top view thereof; and

Fig. 3 is a bottom view thereof.

I claim:

The ornamental design for a hose supporter, substantially as shown.

LEO ZAVOLNER.
